F. G. DIX

LAMP

Filed Mar. 15, 1922

Inventor
Fred G. Dix
Williams Bradley
McCall & Pierce Atty's

UNITED STATES PATENT OFFICE.

FRED G. DIX, OF CHICAGO, ILLINOIS, ASSIGNOR OF ONE-HALF TO OLIVER A. BRANDT,
OF CHICAGO, ILLINOIS.

DESIGN FOR A LAMP.

Application filed March 15, 1922. Serial No. 1,183. Term of patent 7 years.

To all whom it may concern:

Be it known that I, FRED G. DIX, a citizen of the United States, residing at Chicago, in the county of Cook and State of Illinois, have invented a new, original, and ornamental Design for Lamp, of which the following is a specification, reference being had to the accompanying drawing, forming part thereof.

In the drawing:

The figure is a side view of a lamp embodying my new design.

I claim:

The ornamental design for a lamp as shown.

In witness whereof, I hereunto subscribe my name this 10th day of March 1922.

FRED G. DIX.

Witnesses:

J. DAVID DICKINSON,
EDNA V. GUSTAFSON.
